UNITED STATES PATENT OFFICE.

EDWARD H. CROSBY, OF BOSTON, MASSACHUSETTS.

GALVANIC BATTERY.

SPECIFICATION forming part of Letters Patent No. 400,430, dated April 2, 1889.

Application filed January 10, 1889. Serial No. 295,933. (No model.)

To all whom it may concern:

Be it known that I, EDWARD H. CROSBY, of Boston, in the county of Suffolk, State of Massachusetts, have invented a certain new and useful Improvement in Electric Batteries, of which the following is a description sufficiently full, clear, and exact to enable any person skilled in the art or science to which said invention appertains to make and use the same, reference being had to the accompanying drawings, forming part of this specification, in which—

Figure 1 is a vertical transverse section of my improved battery, and Fig. 2 a sectional view showing a modification in the method of connecting the conducting-wire.

Like letters and figures of reference indicate corresponding parts in the different figures of the drawings.

My invention relates especially to that class of electric batteries which are known as "open-circuit" batteries; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the containing-jar, which is constructed of zinc and forms the negative pole of the battery, one of the conducting-wires being attached in any suitable manner thereto. The inner face of the jar is preferably amalgamated with mercury, as shown at x.

In the bottom of the jar is disposed a hard-rubber insulator, b, upon which the carbon pole B rests, said pole being preferably in the form of a pencil.

Surrounding the carbon pencil B at its top and bottom is a hard-rubber insulating-ring, d, the purpose of which is to prevent said pole from being accidentally brought into contact with the jar A.

The jar is filled around the carbon B with a packing, D, consisting of ordinary wool or cotton waste or other spongy material especially prepared with the excitant in the fol-

lowing manner: The wool waste is soaked for some hours in a strong solution of sal-ammoniac, which is then squeezed out of it to carry off the greasy properties of the wool, after which it is again soaked in the solution until thoroughly saturated, when the crystals of the sal-ammoniac will adhere to the wool. The wool, while moist and carrying with it all of the solution it will hold, after the manner of a sponge, is then packed in the jar A around the carbon B. When the carbon pencil is formed, a cap, f, is cast upon its upper end and a conducting-wire cast therein, said cap being composed of a compound of tin and lead. The top of the jar and cap f are then covered by an insulating-cap, g, composed, preferably, of linen prepared with paraffine or similar substance.

The ordinary brass connector, h, may be employed for securing the conducting-wire to the carbon pole, as shown in Fig. 2; but I preferably make use of the cap f, constructed as described, as the fumes arising from the excitant have little or no effect upon it and polarization is thereby prevented.

I find that the electro-motive force of the battery arranged as described is much greater than in batteries of ordinary construction. Its life is also much longer, and it can readily be renewed by moistening the packing D very slightly with water or the solution described, sufficient moisture only being required to affect the sal-ammoniac crystals on the wool.

Having thus explained my invention, what I claim is—

1. In an electric battery, the combination of a zinc-containing jar, a carbon pencil disposed within said jar and insulated therefrom by hard-rubber rings, and a packing disposed around said pencil consisting of wool waste saturated with a solution of sal-ammoniac, substantially as described.

2. In an electric battery, the combination of a zinc-containing jar, a carbon pencil disposed in said jar and insulated therefrom, a packing around said pencil consisting of wool waste impregnated with sal-ammoniac, and a wire-connector on said pencil composed of lead and tin, substantially as described.

3. In an electric battery, the combination of

a zinc-containing jar amalgamated on its inner face, an insulator in the bottom of said jar, a carbon pencil resting therein and provided with insulating-rings, a wire-connector 5 on said pencil composed of lead and tin, an excitant consisting of sal-ammoniac suspended in a sponge-like material around said pencil, and an insulating-cap for said jar, substantially as described.

10 4. In an electric battery, the combination of the zinc-containing jar A, amalgamated at x ,

and provided with the insulator b, the pencil B, having the insulating-rings d, the packing D, disposed around said pencil and composed of wool waste saturated with sal-ammoniac, 15 the wire-connector f, composed of a compound of tin and lead, and the insulating-cap g, all being arranged substantially as described.

EDWARD H. CROSBY.
